UNITED STATES PATENT OFFICE.

ALFRED MOORHOUSE, OF DETROIT, MICHIGAN, ASSIGNOR TO PACKARD MOTOR CAR COMPANY, OF DETROIT, MICHIGAN, A CORPORATION OF MICHIGAN.

CARBURETOR.

Application filed April 30, 1919. Serial No. 293,628.

This invention relates to improvements in carburetors.

The carburetor is of the down draft type.

One object of the invention is to provide

means to prevent flooding of the carburetor.

Another object of the invention is to provide means for producing an emulsion of liquid fuel and air previous to the formation of the final explosive mixture within the main mixing chamber of the carburetor.

Another object of the invention is to provide means for intensifying the suction action through the carbureting elements.

Another object of the invention is to provide means for obtaining a graduating action between the main fuel jet and what is known as the compensating supply which is adapted to balance an increasingly rich mixture from the main jet with an increasingly lean mixture from the compensating means.

Other objects of the invention will appear from the disclosure in the following specification.

With these objects in view the invention is embodied in preferable form in the construction and arrangement hereinafter described and illustrated in the accompanying drawings, in which:-

Fig. 1 is a perspective view, partly broken away to show some of the interior construction in vertical section.

Fig. 2 is a side view, partly broken away, and showing a section on line 2—2 of Fig. 4, with, however, the Venturi tubes in place.

Fig. 3 is a vertical section taken on line 3—3 of Fig. 4, but with the positions of the views reversed.

Fig. 4 is a partial plan and partial horizontal section on line 4—4 of Fig. 2.

Fig. 5 is an end view, partly broken away.

Fig. 6 is a vertical section on line 6—6 of Fig. 4.

Referring to drawings, 10 is a float of usual construction which is mounted in a float chamber 11. An inlet 12 serves to conduct liquid hydrocarbon fuel to said chamber from a suitable source of supply and leads through a chamber 13 and a strainer 14 mounted in said latter chamber. An

inlet bushing 15 provides a passage-way between the strainer chamber and the float chamber and such inlet passage way is controlled by a needle valve 16, operable by the float. Outlet passage-ways 17 lead from the

float chamber through the body of the carburetor to two basin plugs 18 and 19 located in the bottom of wells 20 and 21 respectively.

The well 20 contains a tube 24 for feeding the jet which is subject to the suction of the engine, while the well 21 constitutes a gravity feed well and is open to the atmosphere. This latter well also contains a tube indicated at 42, which supplies the necessary fuel to the engine at idling speeds thereof. The plugs 18 and 19 are threaded in the lower end of that portion of the body of the carburetor which includes the two wells referred to. Above the plug 18 is a calibrated restricting plug 22 which has a small opening at 23 thereto that determines the quantity of the gasoline passing through the passage-way into the jet tube 24. This tube is subject to the suction of the engine and the fuel therefrom is drawn out of the well 20 into the horizontal passage-way 25 and thence through vertical passage-way 26 and horizontal passage-way 27. This passage communicates with a head 28 provided with an annular recess 29 communicating with the openings 30 formed in a Venturi tube 31 which is carried by said head and has its upper end open to the atmosphere and its lower end terminating within an open Venturi tube 32. The fuel feeding holes 30 are located at the line of greatest contraction of the Venturi tube 31 to thereby increase the intermingling force of the air and emulsion. This point of emergence of the fuel into the tube and also the level of the supply passage-way 27 are above the level of the fuel in the float chamber, whereby flooding of the carburetor is prevented. The lower end of the tube 31 terminates at the line of greatest contraction of the tube 32 whereby the latter exerts an ejector action on the former, thereby increasing the velocity head through the contracted part of the small tube. In this way a higher degree of atomization is accomplished in the small tube and there is sufficient suction to raise the fuel from the float chamber 11.

Below the lower end of the Venturi tube 32 is mounted a throttle valve 33 of the butterfly type. This valve is located in chamber 34 and is operated by shaft 35. Referring to Figs. 1 and 6, the well 21 is

provided with a screw plug 36 having a calibrated opening 37 there-through. This well 21 is open to the atmosphere through passage 38 (see Fig. 1), which leads back to the annular chamber 39 surrounding the venturi 32 and which chamber is open to the atmosphere. Owing to this arrangement the fuel in the tube 21 is dependent for its height merely upon the head of the fuel in the fuel chamber. The well 21 communicates by a series of openings 40 arranged at different heights, and having different cross areas, with the well 20 of the main jet and liquid fuel is supplied to the latter well through these openings up to the height of the fuel in the float chamber and as the level of the fuel falls these openings will be successively uncovered and successively permit air to be drawn there-through from the well 21 so as to decrease the richness of the mixture of the fuel supplied from wells 21 and 20. The openings 40 are adapted to be conveniently drilled through openings provided in the outer wall of the well 20 and which are adapted to be closed by the screw plugs 41.

Mounted in the well 21 is an idling tube 42 adapted to supply fuel at idling speeds of the engine. The lower end of this tube 42 dips into the lower part of the well 21 and the upper end of the tube is held in a valve head 43 which is adjustable and is screwed within a bushing 44, which in turn is screwed to the body of the carburetor.

The lower part 45 of said head constitutes a valve and is adapted to seat against a beveled ledge in the bushing 44 in order to close off the well 21. Between said valve and the wall of the bushing is left an annular space 46 adapted to admit air from the well to the passage-ways leading to the throttle and which space is cut off when the valve is moved down against its seat. Openings 47 lead from the tube 42 into said space 46 and through the bushing to permit the passage of liquid fuel from the tube 42 into a horizontal passage-way 47¹. The passage-way 47¹ leads to a vertical passage-way 48 which communicates with a passage 49, (see Figs. 6, 5 and 1) which leads to a point opposite the edge of the throttle valve when the latter is in closed position. When the butterfly valve is entirely closed it seals the outlet of passage 49 (see Fig. 1). When such valve is slightly opened, assuming that the engine is running, a high vacuum is produced, resulting in air blowing past the edge of the valve at a very high velocity, thus causing a high suction on passage 49. This suction is transmitted to passages 48 and 47¹ to holes 47 in the valve 45, as well as to annular passage 46. Since the gravity feed compensating well 21 is full of fuel up to the level maintained by the float, fuel is consequently sucked up the tube 42 through the holes 47 and through the passage 47¹. Air is also drawn past the valve seat and space 46 from the passage-way 38. The quality of the mixture of air and fuel which is drawn through the passage 47¹ is adapted to be regulated by the adjustable valve 45. If this valve is screwed tight against its seat so as to close the space 46, only fuel will be drawn through the holes 47. If the valve be screwed out considerably, the annular passage 46 at the valve seat will be made sufficiently large to satisfy the suction in the passage 47¹, so that only air will be drawn in. It will thus be seen that an intermediate position of the valve 45 can be readily obtained which will give the correctly proportioned quantities of air and liquid hydrocarbon to provide the rich emulsion desired, which is then mingled with the air drawn past the butterfly valve 33, to form the necessary small amount of explosive mixture to maintain the engine running at idling speed. The upper edge of the valve head 43 is serrated and is adapted to be engaged by a spring catch 50 (see Fig. 4).

51 is a hollow rotary altitude valve (see Figs. 2 and 3), having a port 52 adapted to establish communication between the atmosphere and passage-way 26. The function of this valve is to bleed air into the passage 27 through passage 26, when employed on an engine operating at high altitudes, to relieve somewhat the suction existing in chamber or well 20, and thus weaken the mixture.

The invention is shown as applied to a duplex carburetor consisting of two sets of carbureting elements and provided with two throttle valves and two manifold connecting passage-ways so that a separate supply of explosive mixture will be supplied separately to the two sets of cylinders of a V-type motor. The description heretofore has related solely to the carbureting elements of one-half of such duplex carburetor.

The shafts 35 of the two throttle valves carry toothed sectors 53 which mesh with one another so that when one of the shafts is turned as by the lever 54, the throttles will be turned in unison.

In order to prevent an accumulation of liquid fuel if the carburetor is flooded, a drain passage 55 leads from the upper part of the float chamber to the annular space 56 surrounding the outer venturi. The wall of this annular space is provided with a tapped hole 57 adapted to receive a pipe connection for a drain pipe, which may lead outside of the motor and away from the body or fuselage.

The operation of the carburetor is as follows:—

Assuming that the engine is running idle, the throttle valve 33 is slightly open, and air passes the edge of the throttle valve at

high velocity. The valve is so nearly closed, however, that there is very little suction through the Venturi tubes of the carburetor, but there is considerable suction in the passages 49, 48 and 47'. Thus liquid fuel is drawn into the tube 42 from the well 21 and air is drawn from the well 21 which is supplied by the passage 38, the proportion of liquid fuel and air being regulated by means of the adjustable valve head 43. This very rich mixture is, of course, diluted to some extent by the air passing the throttle valve 33, and thus a correct idling mixture is fed to the engine.

As the throttle valve 33 is opened, the main channels for feeding the mixture come into operation because the suction through the Venturi tube 31 is then sufficient to draw the emulsion of fuel through the main passages 25, 26 and 27. Until the level in the well 21 falls below the upper port 40, raw liquid will be drawn both from the wells 20 and 21 into the passage 25, but, of course, the upper port 40 is almost immediately uncovered and it then supplies air which it receives from the port 38, to the well 20, thus forming an emulsion which passes into the passageway 25 and thence through passages 26 and 27 to the Venturi tube 31.

As the throttle valve is opened still farther, thus increasing the suction, the liquid fuel in the well 21 is soon exhausted because the restricted passage 37 supplies the well by gravity only, or substantially so, due to the atmospheric port 38 at the top of the well. Then all of the ports 40 are uncovered and are supplying air to the well 20. The latter well is under the full suction of the Venturi tube 31, except, of course, for the air fed to it through the ports 40, and an increasing amount of liquid fuel is drawn from the tube 24 for emulsion in the well 20 and the passage 25.

From the above it will be seen that the increasing suction on the well 20 tends to increase the liquid fuel fed to the carburetor, and if this well operated alone, the mixture would be too rich at the higher suctions, but the higher suctions soon drain the well 21 and the latter, therefore, supplies a constantly decreasing amount of liquid fuel relative to air and the net result is a substantially constant proportion of liquid fuel and air formed by the carburetor.

It will be understood further that at the lesser throttle openings the well 21 furnishes a reservoir of fuel for supplying the engine while idling, and it also helps to maintain a rather rich mixture for rapid acceleration.

Also, as has been pointed out hereinabove, air may be bled into the passage 26 through the hollow valve 51, which has been described as an "altitude valve" since its principal use

is for operating the carburetor in the higher altitudes where the air is less dense.

Having thus described my invention, what I claim and desire by Letters Patent is:—

1. In a carburetor, in combination with a float chamber, a mixing chamber for effecting final carburetion of the air, a down draft Venturi tube in said chamber including means to admit air and vapor thereto for commingling, the point of said commingling being located above the level of the fuel in the float chamber.

2. In a down draft carburetor, in combination with a float chamber, a liquid fuel supply, a throttle, an upwardly rising liquid fuel tube, a venturi having communication with said tube at the upper end of the latter, said end of the tube being above the level of the said fuel supply.

3. In a down draft carburetor, a throttle valve, a float chamber, an upwardly conducting fuel conduit leading from the chamber, a downwardly conducting venturi leading toward the throttle valve and means to admit fuel from the upper end of the conduit to the venturi.

4. In a carburetor, in combination, means for producing an emulsion of liquid fuel and air, a down draft venturi adapted to receive additional air, and means to admit said emulsion to the venturi to form an explosive mixture with the air therein.

5. In a carburetor, means providing a down draft air passage, a venturi positioned therein, an up draft passage, means to form an emulsion of fuel and air in said up draft passage, and means including a second venturi to discharge the emulsion into the down draft passage.

6. In a carburetor, in combination with a gravity feed well, an idling tube therein for conveying liquid fuel, a passage-way subject to the suction of the engine, a means of communication between said well and said passage-way and between the tube and the passage-way, a valve for controlling said communication and for proportioning the relative quantities of air and fuel passing from said tube and well to said passage-way.

7. In a carburetor, in combination with a gravity feed well, a fuel conveying tube within said well, means of communication between said well and the atmosphere, a passage-way subject to the suction of the engine, means of communication between said tube and said passage-way consisting of an opening through the tube, an annular opening between the wall of the well and said passage-way and an adjustable valve for controlling the size of said annular opening, said opening having communication with said tube opening and with said passageways.

8. In a carburetor, in combination with

a source of supply, a gravity feed well, a float chamber in communication therewith, a drainage chamber open to the atmosphere, a passageway between the upper part of 5 said float chamber and said drainage chamber and a passageway leading from the upper part of said gravity feed well to said drainage chamber.

9. In a carburetor, in combination with 10 idling and main jet wells, a source of liquid fuel supply in communication therewith, a drainage chamber and air connections from said wells to said drainage chamber.

10. In a down draft carburetor, in combination with a float chamber, a main jet well and an idling well, a drainage chamber open to the atmosphere and air connections between said wells and float chamber and said drainage chamber.

20 11. In a carburetor, a float chamber, a gasoline passage leading from the bottom of the float chamber upwardly, a down draft venturi, said passage leading to the venturi

near the upper end thereof and means to admit air to said passage between said chamber and said venturi. 25

12. In a carburetor, the combination of a float chamber, a drainage chamber adjacent to said float chamber, a fuel well supplied by said float chamber, a carbureting chamber, means providing a passage leading from said fuel well to said carbureting chamber, and means providing a valved opening between said drainage chamber and said passage. 30

13. In a carburetor, the combination of a mixing chamber, a drainage chamber surrounding the mixing chamber and open to the atmosphere, a float chamber, idling and main jet wells connected to be supplied by 40 said float chamber and communicating with said mixing chamber, and air connections between said drainage chamber and each of said wells and said float chamber.

In testimony whereof I affix my signature.
ALFRED MOORHOUSE.
